(57) **CLAIM**

The ornamental design for a computer keyboard shell, as shown and described.

DESCRIPTION

FIG. 1 is a perspective view of a computer keyboard shell showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof, shown enlarged in scale;

FIG. 7 is a bottom plan view thereof, shown enlarged in scale;

FIG. 8 is an enlarged view of the computer keyboard shell taken from the circle part in FIG. 2; and,

FIG. 9 is an enlarged view of the computer keyboard shell taken from the circle part in FIG. 3.

The broken lines depict portion of the computer keyboard shell and form no part of the claimed design.
